(57) **CLAIM**

The ornamental design for a sphere target for surveying, as shown and described.

DESCRIPTION

FIG. 1 is a perspective view of a sphere target for surveying showing my new design;

FIG. 2 is a front view thereof, each of a rear view, a right side view, and a left side view being a mirror image of FIG. 2; FIG. 3 is a top view thereof; and,

FIG. 4 is a bottom view thereof.

The broken lines shown in the figures illustrate portions of the shpere target for surveying that form no part of the claimed design.

1 Claim, 4 Drawing Sheets

FIG. 1

FIG. 2

FIG. 3

FIG. 4
